(57) **CLAIM**

The ornamental design for a negative ion straightener comb, as shown and described.

DESCRIPTION

FIG. 1 is a front and right side perspective view of a negative ion straightener comb showing my design according to a first embodiment of the present disclosure.

FIG. 2 is a rear and left side perspective view thereof according to the first embodiment of the present disclosure.

FIG. 3 is a front elevational view thereof according to the first embodiment of the present disclosure.

FIG. 4 is a left side elevational view thereof according to the first embodiment of the present disclosure.

FIG. 5 is a right side elevational view thereof according to the first embodiment of the present disclosure.

FIG. 6 is a rear elevational view thereof according to the first embodiment of the present disclosure;

FIG. 7 is an enlarged bottom elevational view thereof according to the first embodiment of the present disclosure.

(Continued)

FIG. 8 is an enlarged top elevational view thereof according to the first embodiment of the present disclosure.

FIG. 9 is a front and right side perspective view of a negative ion straightener comb showing my design according to a second embodiment of the present disclosure.

FIG. 10 is a rear and left side perspective view thereof according to the second embodiment of the present disclosure.

FIG. 11 is a front elevational view thereof according to the second embodiment of the present disclosure.

FIG. 12 is a left side elevational view thereof according to the second embodiment of the present disclosure.

FIG. 13 is a right side elevational view thereof according to the second embodiment of the present disclosure.

FIG. 14 is a rear elevational view thereof according to the second embodiment of the present disclosure.

FIG. 15 is an enlarged bottom elevational view thereof according to the second embodiment of the present disclosure; and,

FIG. 16 is an enlarged top elevational view thereof according to the second embodiment of the present disclosure.

1 Claim, 16 Drawing Sheets
